Primary Examiner — Patricia A Palasik*(74) Attorney, Agent, or Firm* — Own Innovation Inc.;
Kent C. Howe; James W. Hinton(57) **CLAIM**

The ornamental design for a robotic end effector as shown and described.

DESCRIPTION

FIG. 1 is a front perspective view of an end effector made in accordance with the subject design.

FIG. 2 is a back perspective view thereof.

FIG. 3 is a front view thereof.

FIG. 4 is a back view thereof.

FIG. 5 is a left side view thereof.

FIG. 6 is a right side view thereof.

FIG. 7 is a top view thereof; and,

FIG. 8 is a bottom view thereof.

The broken lines illustrate portions of the article and form no part of the claimed design.

1 Claim, 8 Drawing Sheets(56)
